UNITED STATES PATENT OFFICE.

ADOLPH M. HOLSTEIN, OF SYRACUSE, NEW YORK.

DESIGN FOR A MANUFACTURED FIGURE FOR BRACKETS FOR FURNITURE AND CASKETS
AND FOR INTERIOR AND EXTERIOR DECORATIONS.

52,076.

Specification for Design.

Patented June 4, 1918.

Application filed August 22, 1917. Serial No. 187,563. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for Manufactured Figure for Brackets for Furniture and Caskets and for Interior and Exterior Decorations, of which the following is a specification, reference being had to the accompanying drawing, forming a part hereof.

The drawing is an elevation of my ornamental design for bracket.

This design comprehends the representation of a conventional bracket right angular in general form and supported in the angle thereof by foliated scrolls. The scroll extends from near the end of the horizontal arm of the bracket to near the end of the vertical arm and has the appear-

ance of a molding terminating in scrolls, and the foliated work extends from near the lower end of the scroll where it joins the vertical arm upwardly along the scroll and portions of said foliated work extend into the angle of the horizontal and vertical arms of the bracket. The portion of the scroll beneath the horizontal arm of the bracket where said scroll diverges therefrom is surmounted by a crest of classic leaves which extend to the horizontal arm of the bracket.

I claim:

The ornamental design for a manufactured figure for brackets for furniture and caskets and for interior and exterior decorations, substantially as shown and described.

In testimony whereof, I have hereunto signed my name, at Syracuse, in the county of Onondaga, and State of New York, this 30th day of July, 1917.

ADOLPH M. HOLSTEIN.
